UNITED STATES PATENT OFFICE.

ALICE HARDING BUTLER, OF EVANSTON, ILLINOIS.

GARMENT.

1,305,192.

Specification of Letters Patent. Patented May 27, 1919.

Application filed October 30, 1916, Serial No. 128,391. Renewed July 13, 1918. Serial No. 244,794.

To all whom it may concern:

Be it known that I, ALICE HARDING BUTLER, a citizen of the United States, and a resident of Evanston, in the county of Cook 5 and State of Illinois, have invented certain new and useful Improvements in Garments, of which the following is a specification.

This invention relates to improvements in wearing apparel, and particularly to that 10 class of clothing known as "overalls;" and while it is mainly and especially intended for the use of children, particularly boys, yet it is applicable to garments of either the bifurcated or skirt type, and for adults, 15 as well as children of either sex, and it consists in certain peculiarities of the construction, novel arrangement and operation of the various parts thereof as will be herein-after more fully set forth and specifically 20 claimed.

The principal object of the invention is to provide a garment of the above mentioned 25 and general character which shall be simple and inexpensive in construction, strong, durable, and so made that it can be easily placed on the child or person for wear and use, or removed when desired. Also, so that a certain portion of the garment may be easily 30 attached to or detached from the slip-over or supporting extension thereof, which extension is used for supporting the garment on the shoulders of the wearer.

Other objects and advantages of the invention, will be disclosed in the subjoined 35 description and explanation.

In the accompanying drawing which serves to illustrate an embodiment of the invention,

Figure 1, is a front or face view of the invention embodied in a pair of overalls.

40 Fig. 2, is a rear view thereof showing a portion of the seat flap detached from the front portion of the garment and from the rear portion of the supporting extension and

Fig. 3, is a plan sectional view taken on 45 line 3-3 of Fig. 2, looking in the direction indicated by the arrows, showing the construction of and the manner of securing the side edges of the upper portion of the seat flap to the front portion of the garment and 50 to the rear lower portion of the supporting extension thereof.

Like numerals of reference refer to corresponding parts throughout the different views of the drawing.

55 In the present instance, the garment is shown as a bifurcated one, or in the form of

a pair of overalls but it is apparent that the lower portion of the garment may be of skirt form without departing from the spirit of the invention. The numerals 4 designate 60 the leg portions of the overalls which may be made of any suitable size length and material and after any desired pattern, but in the present case they are illustrated, and in fact the garment is shown as being made of 65 two equally proportioned parts, or halves 5 and 6 sewed together from the crotch 7 to the upper portion of the front and rear portions respectively of the opening 8 in the supporting extension 9 of the garment, so as 70 to permit the shoulders and body of the wearer to occupy the space between the front portion 10 and back portion 11 of said supporting extension.

By reference to Fig. 2, of the drawing, it 75 will be seen that the supporting extension 9, is provided near its lower rear portion with a number of button headed studs 12 which are adapted to engage socket pieces 13 arranged on the inner surface of the upper 80 portion of the seat flap 14, which is free from the sides of the legs downwardly to a suitable point from the waist portion of the garment as at 15, so that when it is desired the seat flap 14, may be attached to the rear 85 lower portion of the supporting extension 9, or readily detached therefrom, in order that the seat flap 14 may be dropped down and outwardly on about a horizontal line from its connection, as at 15, with the outer portion 90 of the legs 4 of the garment. The button headed studs 12 and the sockets 13 therefore, shown, are of substantially the same construction as those used for fastening gloves, but I desire it to be understood that 95 any kind of fastening devices may be employed for connecting the supporting extension 9 near its free end to the upper portion of the waist part of the garment, without departure from the invention. 100

The seat flap 14, is by preference somewhat wider than the width of the extension 9 near its free end, and the seat flap has on the outer surface of the upper portion of each of its sides a stud 12 to engage a socket 105 piece 13 one of which is secured to the inner surface of the front portion of the garment near each side thereof and at about its waist portion as will be readily understood by reference to Figs. 2 and 3 of the drawing. 110

While I have shown the garment as being made of two equal sized portions 5 and 6

which are united together by means of longitudinal and vertical seams 16, yet I desire to be understood that I do not wish to be limited to such construction, as the garment 5 may be otherwise made, or so that the supporting extension 9 may be of a single piece, yet having an opening 8 through which the head and neck of the wearer is projected when the garment is placed in position on 10 the body of the wearer for use, said opening forming shoulder straps 17 to rest on the shoulders and to support the garment. The supporting extension 9 may be a continuous piece or extension from the front portion 15 of the upper part of the garment, and is by preference so made, yet it is obvious that it may be sewed or otherwise attached to the front upper or rear upper portion of the garment with an opening 8, as shown, and 20 yet be within the province of my invention.

From the foregoing and by reference to the drawing it will be readily understood and clearly seen, that by my improvements a very comfortable, useful, and serviceable 25 garment or pair of overalls will be afforded, in which a child may be readily clothed by simply placing the legs or lower portion of the garment on the child and by then placing the supporting flap over the head of 30 the child and then fastening the seat flap to the lower free portion of the supporting extension. When the garment is thus in position on the wearer it is obvious that the shoulder straps 17 will rest on the shoulders 35 and securely and comfortably support the garment. The seat flap 14 is by preference provided with a fold 21 (see Fig. 2) at each of its side edges near the upper portion thereof, and as before stated this flap is 40 somewhat wider than the width of the free portion of the supporting extension so that the flap may be extended around the side of the waist of the wearer, and fastened by means of the fastening devices 12 and 13,

or otherwise, to the front portion of the garment at about the waist line thereof. 45

Having thus fully described my invention, what I claim as new and desire to secure by Letters Patent is—

As an improved article of manufacture, a 50 garment consisting of two single pieces of the same configuration, each of said pieces having an extension at its front and rear upper portions, the lower portion of each piece being folded upon itself and the edges 55 thereof sewed together to form coverings for portions of the legs of the wearer, the said sewed portions being located on the adjacent sides of the leg coverings and united at their upper ends to form a crotch, the extensions 60 of the rear upper portions of the leg portions being projected upwardly to about the waistline of the wearer and sewed together at their adjacent edges to form a seat-flap, the said extensions of the upper part of the 65 other pieces being projected upwardly therefrom and sewed together at the lower part of their adjacent front edges, then formed to lie over the shoulders of the wearer to form a support for the garment, then ex- 70 tended downwardly and sewed together at their lower meeting edges, the last named extensions having an elongated opening between their adjacent edges, said opening being contracted at each of its ends and so 75 located that one of its contracted portions will be in the front of the wearer and the other contracted portion at the rear of the wearer, the said last named or supporting extensions having one of their ends free, and 80 means to detachably connect said free portion thereof to the upper portion of the seat-flap.

ALICE HARDING BUTLER.
